UNITED STATES PATENT OFFICE.

WILLIAM E. DIEHL, OF CHICAGO, ILLINOIS.

SAFETY POCKET.

Application filed May 2, 1922. Serial No. 557,927.

To all whom it may concern:

Be it known that I, WILLIAM E. DIEHL, a citizen of the United States, and a resident of the city of Chicago, county of Cook, 5 and State of Illinois, have invented certain new and useful Improvements in Safety Pockets, of which the following is a specification.

This invention relates to improvements 10 in safety pockets, and has for its object the provision of a pocket of this character particularly designed for use in connection with a watch to prevent accidental or surreptitious removal thereof from the pocket.

15 Other objects will appear hereinafter.

The invention consists in the combinations and arrangements of parts herein-after described and claimed.

The invention will be best understood by 20 reference to the accompanying drawings forming a part of this specification, and in which,

Fig. 1, is a fragmentary view of a garment having a pocket therein, showing my 25 invention applied thereto,

Fig. 2, is a similar view showing the invention in inoperative position, and

Fig. 3, is a sectional view on line 3—3, 30 Fig. 1.

The construction hereinafter described is 35 an improvement over that set forth in United States Letters Patent No. 1,296,168 granted to me March 4, 1919, and is designed to greatly simplify the construction shown in said patent, and also lessen the cost of production thereof.

The invention may be used in connection 40 with pockets of any garment, such as waist-coats, trousers and the like. As shown in the drawings, 10 represents a garment, in this particular instance, a pair of trousers, such trousers having a pocket 11 of the type ordinarily provided for carrying a watch therein. Such pocket 11 may be provided 45 with an opening 12 in its outer side, such opening being preferably situated a suitable distance from the upper edge of said side, and offset with respect to a vertical center line extending through said pocket.

50 Secured to the outer side of the pocket 11, preferably at the edge thereof, above the opening 12, is a depending flap 13, such flap preferably having a male member 14 of a snap fastener secured to its under side 55 in line with and adapted to project through the opening 12, and in operative position

to engage a related female member 15 secured to the inner side of the pocket 11, thereby simultaneously closing the mouth of the pocket and securing the flap 13 in 60 position.

As stated, the invention is particularly 65 designed to prevent theft, or accidental removal of a watch from the pocket, and the embodiment of the invention described is capable of use in several different ways to accomplish this result. When a watch not having a chain or fob attached thereto is placed in the pocket, the fastener restricts the mouth of the pocket to such an extent 70 that the watch cannot pass through the openings on each side thereof, and due to the fact that the fastener merely divides the mouth of the pocket into smaller openings other and smaller objects may be inserted 75 into the pocket without interfering with the fastener. When the watch is provided with a fob or chain, as shown in Fig. 1, the chain may extend outwardly through the smaller opening formed by the fastening 80 means, thus providing a double lock. If desired, the larger opening formed by the fastening means may be large enough to permit the extraction of the watch there-through, in which case the watch can be extracted, but the chain or fob will remain 85 in the smaller opening thereby preventing complete separation of the watch from the pocket. Also, if desired, instead of passing the chain through the smaller opening, as 90 shown in Fig. 1, such chain may extend to the outside of the pocket and laterally beneath the flap 13, which, in operative position, forms a loop between its secured end and the fastener, in this manner also 95 accomplishing a result similar to that just described.

While I have illustrated and described the preferred form of construction for carrying my invention into effect, this is 100 capable of variation and modification without departing from the spirit of the invention. I, therefore, do not wish to be limited to the precise details of construction set forth, but desire to avail myself of such 105 variations and modifications as come within the scope of the appended claims.

Having described my invention, what I claim as new and desire to secure by Letters Patent is:

110 1. The combination with a garment pocket, of means for securing the mouth of

- 5 said pocket together, said means including a movable member secured at the outside of said pocket, and having a fastener mounted thereon, said fastener having a portion extensible through the outer side of said pocket, said portion being adapted to be detachably fastened to the inner side thereof, and in inoperative position to be removable from the interior of said pocket.
- 10 2. The combination with a garment pocket, of means for securing the mouth of said pocket together, said means including a movable member secured at the free edge of the outer side of said pocket, and having a fastener thereon, said fastener having a portion extensible through the outer side of said pocket, said portion being adapted to be detachably fastened to the inner side thereof, and in inoperative position to be removable from the interior of said pocket.
- 15 3. The combination with a garment pocket, of means for securing the mouth of said pocket together, said means including a flap secured to the free edge of the outer side of the pocket, at a point nearer to the middle of the pocket opening than to the ends, the longitudinal axis of said flap extending transversely of the pocket opening, said flap having a fastening member thereon; and a fastening member on the inner side of said pocket arranged to engage said first named fastening member.

4. The combination with a garment pocket, of means for securing the mouth of said pocket together, said means consisting of a flap secured to the upper edge of the outer side of said pocket, there being an opening in the outer side of said pocket adjacent the end of said flap; and a fastener on said flap having a portion extensible through said opening and engageable with a related fastener on the inner side of said pocket and in inoperative position to be removable from said opening.

5. The combination with a garment pocket, of means for securing the mouth of said pocket together, said means consisting of a flap secured to the outer side of said pocket, there being an opening in the outer side of said pocket adjacent the end of said flap; and a fastener mounted on said flap in line with said opening, and having a portion extensible through said opening and engageable with a related fastener on the inner side of said pocket, and in inoperative position to be removable from said opening.

In testimony whereof I have signed my name to this specification in the presence of two subscribing witnesses.

WILLIAM E. DIEHL.
